HENRI GRASSET, OF PARIS, FRANCE.

APPARATUS FOR FUMIGATING DENTAL CAVITIES.

1,116,056.

Specification of Letters Patent.

Patented Nov. 3, 1914.

Application filed May 21, 1914. Serial No. 840,002.

To all whom it may concern:

Be it known that I, HENRI GRASSET, the above-named petitioner, a citizen of the Republic of France, and resident of Paris, France, have invented a new and useful Apparatus for Fumigating Dental Cavities, which is fully set forth in the following specification.

This invention relates to apparatus for fumigating dental cavities by treating the same with vapors of iodin or other drugs.

Such apparatus, as ordinarily constructed, includes a metal body portion made of two or more sections detachably connected together and adapted to contain the medicinal substance, the latter being vaporized by contact with a heated gaseous medium that is blown through the said body. In practice, however, apparatus constructed as just described has proved objectionable, since the iodin vapors, in passing therethrough, have a corroding action upon the metal, which soon renders the apparatus useless.

It is the object of my invention, therefore, to overcome this defect by utilizing within the body of the apparatus an improved container for the medicinal substance which is made of non-corrodible material and is so constructed and arranged as to prevent the vapors from coming into contact with the walls of the said body, and filtering through the joints thereof, while, at the same time, interfering in no way with the access of the heated gaseous medium to its contents.

An embodiment of the invention is illustrated in the accompanying drawing, wherein: —

Figure 1 is a fragmental view of the improved apparatus, partly in elevation and partly in section. Fig. 2 is an elevation of the complete apparatus; and Fig. 3 is a fragmental sectional view showing a modified means for heating the gaseous current.

In the apparatus in question, the iodin, iodoform or other drug to be vaporized, or the cotton wool or other absorbent material impregnated with a solution of such drug, is deposited in a cup 1, which is made of steatite or other non-corrodible material. This cup is disposed within the section 3

of the body of the apparatus, and at its mouth is arranged a pad 2, likewise made of steatite, which pad is provided with a central conduit 6 that projects into said cup. The other section 4 of said body is then threaded upon the section 3, and the two sections are then screwed together, thus pressing the pad tightly against the cup, the heated air or other gas being admitted into said cup through an opening 5 in the bottom thereof, whence it passes through the conduit 6 and into the nozzle 9, carrying with it the vapors generated by the iodin or other drug. The arrangement is such, therefore, that the said vapors are completely prevented from attacking the walls and joints of the body of the apparatus, so that the rapid corrosion and consequent destruction thereof are in this way avoided.

In the construction illustrated, the body of the apparatus has a widened portion 7 which can be readily heated in the flame of a Bunsen burner; but the heating may, of course, be effected in various other ways, for instance, by passing an electric current through a resistance element 10, Fig. 3, located in a chamber 11 provided in the apparatus in front of the cup. In such case, the apparatus may be provided with a nipple 12, which is adapted for connection with a blower or other source of air or gas supply, (not shown). The air or gas may, also, be blown in either by means of a bulb 8, as shown in the drawing, or in any other suitable manner. The nozzle 9 may have any form suitable for the treatment to be effected, the end of the said nozzle being introduced into the cavity under treatment, as will be understood.

Claim:

An apparatus for fumigating dental cavities comprising a body having an internal passage for the circulation therethrough of a heated, gaseous medium, said body being composed of alining, tubular sections having their presented ends coupled together; a cup of non-corrodible material fitted in said passage at the junction point of said sections and adapted to contain a medicinal substance vaporizable by the heated, gaseous medium, said cup having an opening to

permit access of said medium to its contents; a pad of non-corrodible material arranged at the mouth of said cup and provided with a conduit projecting thereinto; 5 and a nozzle located at the outer end of one section.

In testimony whereof I have signed this

specification in the presence of two subscribing witnesses.

HENRI GRASSET.
